United States Patent Office

Des. 233,166
Patented Oct. 8, 1974

233,166

LIGHT FIXTURE

Fred M. Gore, Dallas, and Ralph M. McFarlin, Pasadena,
Tex., assignors to Esquire, Inc., New York, N.Y.

Original design application Apr. 11, 1973, Ser. No.
350,154. Divided and this application Dec. 7, 1973,
Ser. No. 422,832

Term of patent 14 years

Int. Cl. D26—03

U.S. Cl. D48—31

FIG. 1

FIG. 2

FIG. 3

FIG. 4

FIG. 5

FIG. 6

FIG. 7

FIG. 1 is a side view of a light fixture embodying our design;

FIG. 2 is right end view thereof;

FIG. 3 is a top plan view thereof;

FIG. 4 is a perspective view of a second embodiment of our design;

FIG. 5 is a perspective view of a third embodiment of our design;

FIG. 6 is a perspective view of a fourth embodiment of our design.

This is a division of design application Ser. No. D. 350,154, filed Apr. 11, 1973.

We claim:

The ornamental design for a light fixture, substantially as shown and described.
